[57] ABSTRACT

A spring leaf comprising an integral substantially cylindrical eye structure on at least one of its ends consisting essentially of adjacent parallel portions cylindrically curved in opposite directions out of the plane of the leaf.

SPRING LEAF

This invention relates to spring leaf structure and particularly to the end formation commonly known as the eye for connecting the spring end or ends to frame pivots, shackles and the like.

It has been generally conventional to form these spring eyes integral with the spring leaf by suitably turning over the spring end to provide a cylindrical bosslike formation adapted to fit over the pivot or shackle pin. In this conventional eye formation, the eye may be disposed above or below the plane of the leaf, usually above, or with its center in the plane of the leaf which is the so-called Berlin eye. In all forms, the entire leaf end is reversely turned over in a rolling or equivalent operation until the end edge substantially abuts a leaf surface.

Difficulties have been encountered in these conventionally formed eyes because the entire width of the leaf is curved in one direction and the eye under driving and braking leads is subjected to bending moments. These bending moments tend to open and otherwise deform the eye and create bending stresses of high magnitude. Since bending stresses are highest at the surface of the leaf, stress raisers and abrasion at the surface are very critical to fatigue life.

The major object of the invention is to provide a novel spring eye structure wherein the stresses are distributed across the section of the leaf by substantial elimination of the bending moments during operation of the vehicle.

More specifically the present invention contemplates reducing the foregoing difficulties by providing a novel leaf spring eye structure wherein integral parallel oppositely curved end portions form the spring eye and this is another object of the invention.

It is further object of the invention to provide a novel leaf spring eye structure of cylindrical contour wherein adjacent spring leaf end portions are oppositely uniformly curved about a common center.

Another object of the invention is to provide a novel integral leaf spring eye structure consisting of adjacent oppositely curved end portions which have their terminal edges adjacent and facing each other near the juncture between the spring eye and the leaf.

BRIEF DESCRIPTION OF DRAWINGS

FIG. 1 is a side elevation showing a spring leaf according to a preferred embodiment of the invention;

FIG. 2 is a partly broken away fragmentary side elevation showing one end of a spring leaf formed according to the invention;

FIG. 3 is end view of the spring leaf of FIG. 2;

FIG. 4 is top plan view of the spring leaf of FIG. 2;

FIG. 5 is a fragmentary side elevation of a spring end illustrating a further embodiment;

FIG. 6 is an end view of the spring of FIG. 5;

FIG. 7 is a fragmentary plan view showing the spring end of FIG. 5.

FIG. 8 is a fragmentary side elevation showing an end of a spring leaf formed according to a further embodiment;

FIGS. 9 and 10 are respectively plan and end views of the spring end of FIG. 8;

FIG. 11 is a fragmentary side elevation showing an end of a spring leaf formed according to a still further embodiment; and

FIGS. 12 and 13 are respectively plan and end views of the spring end of FIG. 11.

PREFERRED EMBODIMENTS

FIG. 1 shows a single tapered spring leaf 11 incorporating the invention. The spring leaf is preferably an integral member of some alloy steel or carbon steel or other suitable material conventionally used for vehicle springs. This spring leaf may be of the type having a center section 12 of maximum thickness, usually medially secured to an axle indicated at A, and end sections that gradually reduce in thickness from the center section toward the spring ends. Preferably the spring

leaf is of constant width from end to end, and is of uniform size at the opposite end sections. Spring leaf 11 has a flat planar surface 14 along its entire length at one side, and at the other side the tapered surfaces 15 and 16 extend at an angle relative to surface 14.

Spring leaf 11 may advantageously be the tapered leaf spring disclosed in Greene et al. U.S. Pat. No. 3,238,072, and made by the method disclosed in that patent, including forming surfaces 15 and 16 by roll tapering, except that the spring ends in the present invention are formed in a novel manner to provide a novel spring eye structure as will appear. The invention may be applied to any spring leaf, including for example the types disclosed in Komarnitsky U.S. Pat. No. 3,339,908, and Schilling Pat. No. 2,608,752, and the top leaf of an otherwise conventional multileaf spring bundle.

Referring to FIGS. 2-4, there is shown one end of spring leaf 11. The other end is preferably identical. The spring end is integrally formed to provide an eye structure 17 adapted to connect the spring end to a pivot on the chassis C or on a shackle S (FIG. 1).

The integral eye structure 17 consists essentially of a central end portion 18 of the spring end bent upwardly out of the plane of the leaf in a smoothly curved junction 19 and then counterclockwise outwardly, downwardly and back inwardly around in substantially circular curvature to locate its terminal edge 20 adjacent the underside of the leaf at junction 19. Two spring end portions 21 and 22, of the same length as portion 18 and disposed on opposite sides of portion 18, are similarly but reversely bent downwardly out of the plane of the leaf in a smoothly curved junction 23 and then upwardly around in a substantially circular curvature to dispose their terminal edges 24 adjacent the upper side of the leaf adjacent junction 23. Junctions 19 and 23 are adjacent and identical but oppositely curved.

As shown the leaf end portions 21 and 22 are each of about one-half the width of central portion 18. The inner surface 25 of leaf end portion 18 is a cylinder having its center on the longitudinal axis of the leaf, and the inner surfaces 26 of the outer side portions 21 and 22 are cylinders of the same radius about the same center. Thus the cylindrical surfaces 25 and 26 which have a common center define an eye structure adapted to pivotally fit over a bushing, a chassis mounted pivot or shackle pin in the usual manner.

Preferably the spring eye 17 is formed by cutting parallel slits 27 and 28 of equal length and proper lateral spacing at the ends of the otherwise complete spring leaf, and then subjecting the end portions 18, 21 and 22 to a suitable rolling or equivalent forming operation to provide the cylindrical eye structure.

It will be understood that if desired the cylindrical eye can be formed by reversely bending the central and side end portions of the leaf respectively oppositely to the above described directions.

FIGS. 5-7 illustrate another embodiment of the invention wherein the cylindrical eye structure 29 is formed above the level of the leaf 11. In this embodiment the central end portion 31 is bent upwardly out of the plane of the spring leaf in a smoothly curved junction 32 and then outwardly, downwardly and back inwardly to dispose its terminal edge 33 adjacent junction 32. The two equal width end portions 34 and 35 on opposite sides of central portion 31 extend past junction 32 and are reversely bent in a substantially circular clockwise curvature upward out of the plane of the leaf and then inwardly and downwardly to dispose their terminal edges 36 adjacent junction 32 and substantially in the same radial plane as edge 33.

The cylindrical inner surface 38 of leaf end portion 31 has the same radius as the coaxial cylindrical surfaces 39 of the end portions, so that a cylindrical eye structure is provided at 29 for pivotal connection to the chassis or shackle as in FIG. 1.

It will be understood that if desired the eye 29 may be formed by curving the central and end portions respectively oppositely to the above-described directions, or by curving

these central and side portions to dispose the cylindrical eye on the underside of the spring leaf.

FIGS. 8-10 illustrate another embodiment wherein the cylindrical eye structure 40 is formed of two oppositely curved adjacent end portions 41 and 42 instead of three as in FIGS. 2-4. Here the spring leaf end is longitudinally slitted back from the end edge a suitable amount, this slit being preferably medial as indicated at 43. The end portion 41 at one side of the slit is bent upwardly out of the plane of the leaf in a smoothly curved junction indicated at 44, and the other end portion 42 is bent downwardly out of the plane of the leaf in a smoothly curved junction indicated at 45.

The reversely curved end portions 41 and 42 have aligned coaxial circularly cylindrical inner surfaces 46 and 47 respectively, and the terminal edges 48 and 49 of the respective end portions face each other adjacent the juncture of the eye with the leaf.

FIGS. 11-13 illustrate another embodiment wherein the cylindrical eye structure 50 is formed of two oppositely curved adjacent end portions 51 and 52, instead of three as in FIGS. 5-7. Here the spring leaf end is longitudinally slitted back from the end edge a suitable amount, this slit being preferably medial as indicated at 53. The end portion 51 at one side of the slit is bent upwardly out of the plane of the leaf in a smoothly curved junction indicated at 54, and then outwardly, downwardly and back inwardly to dispose its terminal edge 55 adjacent junction 54. The other end portion 52 is reversely bent in a circular clockwise curvature upwardly out of the plane of the leaf and then inwardly and downwardly to dispose its terminal edge 56 adjacent juncture 54 and substantially in the same radial plane as edge 55.

The reversely curved end portions 5 and 52 have aligned coaxial circularly cylindrical inner surfaces 57 and 58 respectively.

In all embodiments of the invention the eye consists essentially of at least two side-by-side adjacent oppositely curved end portions of the spring leaf. Preferably in all embodiments the total cylindrical inner bearing areas curved in opposite directions are substantially equal.

The invention may be embodied in other specific forms without departing from the spirit or essential characteristics

thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by Letters Pat. is:

1. A spring leaf comprising an integral substantially cylindrical eye structure located at least at one of its ends consisting essentially of adjacent end portions curved in opposite directions out of the plane of the leaf, the terminal edges of said spring end portions being disposed adjacent the juncture of the eye structure with the leaf.

15 2. A spring leaf as defined in claim 1, wherein at least one of spring end portions is connected to the leaf by a smoothly curved junction and the terminal edges of all of said spring end portions are disposed adjacent said junction.

20 3. A spring leaf as defined in claim 1, wherein the total internal bearing surface area of the portions curved in one direction are equal to the total internal bearing surface areas of the portions curved in the opposite direction.

25 4. A spring leaf as defined in claim 1, wherein said eye structure comprises an intermediate end portion curved in one direction out of the plane of the spring leaf, and adjacent opposite side edge portions curved in the opposite direction out of the plane of the spring leaf.

5. The spring leaf defined in claim 4, wherein said intermediate portion is centrally disposed and of approximately twice the width of each side edge portion.

30 6. The spring leaf defined in claim 4, wherein said intermediate and side edge portions are of the same length.

35 7. The spring leaf defined in claim 4, wherein said intermediate portion is connected to said leaf by a smoothly curved junction, and the terminal edges of all of said portions are disposed adjacent said junction.

8. The spring leaf defined in claim 1, wherein said eye structure comprises two side-by-side cylindrical portions oppositely curved out of the plane of said spring leaf.

9. The spring leaf defined in claim 8, wherein said curved end portions are of substantially equal width.

UNITED STATES PATENT OFFICE
CERTIFICATE OF CORRECTION

Patent No. 3,645,522

Dated February 29, 1972

Inventor(s) FREDERICK T. ROWLAND

It is certified that error appears in the above-identified patent
and that said Letters Patent are hereby corrected as shown below:

Column 2, line 33, change "supper" to read "upper"

Column 3, line 32, change numeral "5" to numeral "51"

Signed and sealed this 8th day of May 1973.
